UNITED STATES PATENT OFFICE

JOHN B. OLSON, OF FORT ATKINSON, WISCONSIN, ASSIGNOR TO JAMES MANUFACTURING COMPANY, OF FORT ATKINSON, WISCONSIN, A CORPORATION OF WISCONSIN

MANGER STRUCTURE

Application filed April 24, 1930. Serial No. 446,822.

My invention relates to improvements in manger structures.

A primary object of this invention is to provide means whereby the base portion and the alley way along which the attendant passes in front of the cattle or other animals may be constructed of concrete or similar material in one unit of such form that the base of the manger constitutes a mere depression 10 along one margin of the alley floor with no permanent dividing wall between them, the back wall of the manger above the alley floor comprising a swinging member which may be moved out of the way to facilitate cleaning 15 the manger or moving material from the alley floor into the manger, either with a broom, shovel or other implement.

Further objects of my invention are to reduce the cost of the concrete portions of manger and alley floor structures, to provide means for promoting sanitation, to provide means whereby the front or alley wall of the manger may be made of any desired height, while increasing instead of reducing the convenience of access and in general, to provide 25 a better and more serviceable manger structure than those which have heretofore been used.

In the drawing:

30 Figure 1 is an elevation of a portion of a manger structure as seen from the front or alley side.

Figure 2 is a sectional view, drawn generally to line 2—2 of Figure 1.

35 Like parts are identified by the same reference characters in both views.

The base portion of my improved manger structure has the form of a shallow trough. The stable floor or floor receiving bed 10 is 40 separated from the manger by a stanchion frame sill 11 which also forms the rear wall of the manger. A depressed trough-like portion 12 constitutes the bottom portion of the manger and extends along the front side of the sill between it and an alley floor 13. If desired, the stable floor 10, sill 11, manger base 12 and alley floor 13 may be formed integrally of concrete or equivalent material.

50 The stanchion frame posts 14 may be secured to the sill 11 in any ordinary manner

and these posts are preferably provided with manger partitions 16, preferably formed of metal plates and connected to the posts 14 by arms 17, pivoted to the brackets 18. These partitions may be swung upwardly about 55 their pivotal axes 19 to facilitate cleaning the manger.

Another line of posts 22 extends along the front or alley side of the manger with their upper portions connected by a rail or longitudinally extending rod 23, this rail being secured to the posts by clamping brackets 24. These posts have elbowed extensions 25 which may be secured to the posts by the same clamping brackets. The extensions curve 65 rearwardly and support a guard rod or rail 26. In the construction shown, the lower ends of the posts 22 are embedded in concrete and reinforced axially by anchor members 27.

Between the alley 13 and the manger 70 trough or base portion 12 there is an inclined manger wall member 30. The upper margin of this wall member is provided with elbowed hangers or hinge members 31 which are pivotally socketed in the brackets 24, each 75 bracket 24 having pivot receiving sockets 32.

The wall member 30 is preferably formed of sheet metal having its lower margin folded upon itself as indicated at 35 and its upper margin, between the hinge members 31, 80 turned forwardly and folded upon itself to form a reinforced marginal flange or bead 36. It is not material to the invention herein claimed whether the wall 30 is formed in sections, with each section equal in length to 85 the distance between the posts 22 or whether it is continuous throughout the length of the manger. If continuous, its upper margin will, of course, be notched or shaped in such a manner that the wall member will not strike 90 the post when it swings downwardly to its normal inclined position, in which position its reinforced lower margin will rest against the edge margin of the alley floor 13 partially within the permanent or base portion of the 95 manger.

The manger wall 30 may be swung upwardly upon its pivotal connections with the brackets 24 as indicated by dotted lines in Figure 2. I preferably form these wall 100

members 30 in sections which are substantially equal to the distance between centers of the posts 22 as shown in Figure 1 in order to facilitate swinging the front 30 of each 5 manger section upwardly, independently of the other sections. The guard rail 26 may conveniently be provided with hooks 37 adapted to engage notched margins of the sections of the wall member 30 to hold them 10 in a raised position as clearly indicated in Figure 2. The lower margin 35 may also be notched to receive the manger partition, or if desired, the partition 16 may be raised before swinging the wall member 30 or any 15 section thereof, upwardly.

The longitudinal rods or rails 23 and 26 serve as guards to prevent hay from being thrown out of the manger by the animals. The sections 30 serve a similar purpose as 20 to all materials placed in the manger. The use of the swinging wall member 30 makes it possible to employ the guard rails 23 and 26 without interfering with the operation of filling the manger from the alley, this 25 operation being performed by swinging the manger wall or wall section 30 inwardly. Preferably these wall sections are so made that they may swing freely under pressure of a fork or shovel or material that is being 30 handled, thereby, and therefore, when filling the manger, it is unnecessary to first fasten the sections of the wall 30 in the raised position. When cleaning the manger or when 35 for any other reason it is desirable that the wall member or members 30 shall be supported in a raised position to allow free passage of material to or from the base portion of the manger, the wall member or members 30 will, of course, be fastened in 40 the raised position by the hooks 37 or equivalent means.

It will be understood that with the above 45 described construction in which a guard frame is provided at one side of the manger and a stanchion frame at the other side, it becomes possible to swing the wall members 50 upon pivotal supports along their upper margins to positions of non-use without interfering with the animals and without lifting these manger wall members to a greater 55 height than that of an ordinary stable, whereas similar wall members supported from a stanchion frame, if similarly pivoted and swung upwardly, would strike the heads of the animals and, if lifted pivotally above the 60 heads of the animals, abnormally high stables would be required and the wall members would also tend to frighten the animals when lifted and swung in their direction.

60 I claim:

1. A manger having a stanchion frame along its rear side and a guard frame along its front side, in combination with a manger 65 wall member pivoted to the guard frame and free to swing upwardly to raised position,

said guard frame having an overhanging portion provided with means for engaging and supporting the manger wall member in its raised position.

2. A manger structure comprising the 70 combination of a fixed manger base having a stanchion frame at one side and a set of manger wall supporting posts at the other side, a movable manger wall pivoted to said wall supporting posts and adapted to be swung upwardly to a raised position at the side of the manger opposite the stanchion frame, whereby said wall when raised may be supported out of reach of the head of the animal occupying an associated stall. 75

80 3. A manger structure comprising the combination of a manger base having an alley floor at one side and a stanchion frame at the other side, said alley floor being at a level to allow material to be freely pushed therefrom to the manger base, a movable manger wall normally sub-dividing the space above the alley floor from that above the manger base, and means for pivotally supporting the upper marginal portion of 85 said wall to allow the lower margin to be swung upwardly and either allow material to be pushed from the alley floor to the manger base or allow said wall to be adjusted to a raised position out of reach of animals 90 secured at the other side of the manger base. 95

4. A manger structure comprising the combination with a manger base having a stanchion frame at one side and an alley floor at the other side provided with a raised 100 guard frame, a movable manger wall connected with the guard frame and normally downwardly inclined in the direction of the manger base on the side opposite the stanchion frame, and means for adjusting and supporting said wall from the guard frame in a raised position in front of and above the space within which animals connected with the stanchion frame may swing their 105 heads. 110

5. A manger base having a stanchion frame at one side and a set of posts at the other side, in combination with a movable manger wall pivotally connected with said posts and normally inclined downwardly and rearwardly, with its lower margin engaged with the manger base, said wall being adapted for swinging movement upon its pivotal connections to a raised position out 115 of reach of animals connected with the stanchion frame. 120

6. A manger base having a stanchion frame at one side and manger wall supports at the other side, and a movable manger wall having its upper margin pivotally connected with the supports, said wall normally having its lower margin resting loosely upon the manger base opposite the stanchion frame and adapted to yield under pressure of ma- 125 130

terial that is being pushed from the alley floor in the direction of the manger base.

7. A manger structure comprising the combination with a manger base, of a stanchion frame extending along one side thereof, manger wall supports at the other side thereof, and a manger wall having its upper portion connected with said supports for oscillation about an axis extending along its upper margin, the lower margin of said wall being free to yield in the direction of the manger base and to be swung upwardly therefrom.

8. A manger structure comprising the combination of a manger base flanked on one side by a stanchion frame and on the other side by an alley floor, a manger wall normally separating the manger base from the alley floor and adapted to yield under pressure of material on the alley floor when pushed in the direction of the manger base, and means for holding said wall against movement in the direction of the alley.

9. A manger having a stanchion frame at its rear side and a movable front wall member at the other side, in combination with means for supporting said movable front wall member in an elevated position out of reach of animals connected with the stanchion frame.

10. A manger base having a stanchion frame at one side and a guard frame at the other side, in combination with partition members pivoted to the stanchion frame for swinging movement to raised positions, and manger wall members pivoted to the guard frame and adapted to be swung to raised positions on the opposite side of the manger base from that occupied by the stanchion frame.

JOHN B. OLSON.
